UNITED STATES PATENT OFFICE.

JOHN HUME BELL, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,265,728.

Specification of Letters Patent. Patented May 14, 1918.

Application filed July 12, 1917. Serial No. 180,168.

To all whom it may concern:

Be it known that I, JOHN H. BELL, a citizen of the United States, residing at East Orange, in the county of Essex and State of

5 New Jersey, have invented certain new and useful Improvements in Telegraph Systems, of which the following is a full, clear, concise, and exact description.

This invention relates to telegraph systems and more particularly to telegraph receiving apparatus and systems for reproducing telegraphic signals in the form of a printed record.

The object of this invention is to provide 15 a telegraph receiver capable of performing the necessary functions in a reliable and efficient manner to render service of particular value in connection with line conductors having low time constant characteristics as 20 in submarine cable working.

This invention provides a line relay responsive to alternating current impulses and adapted selectively to close different contacts, depending upon the amplitude of the 25 received current. These contacts in turn control the circuits of a group of selectively operated selecting relays, a distributor being provided for completing the circuits from the line relay to the selecting relays 30 sequentially in synchronism with the receipt of the line signals.

The present receiving equipment preferably responds to telegraphic signals formed of three-unit code impulses comprising 35 three successive alternations or one-half cycle currents formed from combinations of currents of predetermined strength and first and second incremented values thereof. A suitable arrangement not shown but well understood 40 in the art is to be employed for driving the distributor in such phase with incoming impulses from the line, that in unison with each impulse the distributor will be effective over certain radially associated pairs of segment contacts.

This invention is illustrated in the accompanying drawing, in which only so much of a telegraph receiving equipment is shown as will be necessary for a clear understanding 50 of this system. Figure 1 is a diagrammatic illustration of a preferred embodiment of this invention, while Fig. 2 similarly illustrates an alternative arrangement.

Referring to the drawing, the selective action 55 set up by a combination of three-unit

code impulses will be traced, as such descriptions will be sufficient to afford a clear understanding of the feature of the present system.

For convenience let it be assumed that a 60 three-unit code signal formed of an alternation of minimum current strength and positive polarity, an alternation of negative polarity incremented to a mean current strength, and an alternation of positive polarity 65 incremented to a maximum current strength suitable for selecting a letter, say F, will be received over a line conductor 1. Accordingly, the first weak impulse of current on traversing a primary winding 3 of a transformer 4 to a ground connection 2 sets up a corresponding current action in the secondary winding 5 of the transformer. A moving coil 11 of a gold wire relay 10 (of well-known type) included with the secondary 70 winding 5, although affected by this weak current impulse is not sufficiently stressed to cause a gold wire tongue 12 (moved by a physical connection with the coil 11 not shown) to move with sufficient amplitude to 75 touch either one of the associated double prong-like contacts of the contact members 14 and 16. Although the trailer arm 21 in synchronism (by means not shown) with the first impulse of current is present over the 80 segments 30 and 40, no action takes place due to the marginal non-operation of the relay 10 as described. The next impulse of current being incremented to a mean predetermined strength, the moving coil 11 of 85 the relay 10 will stress the tongue 12, say, against the right-hand prong of the contact 16. The arm 21 of the distributor 20 moving in step with the impulses of current from the line 1 will at the same moment be 90 present over the segments 50 and 60, thereby completing a circuit prepared by the relay 10. This circuit extends from a source 8, current bus 9, contacts 12 and 16 of the relay 10, conductor 17, contactor ring 27 of 95 100 the distributor 20, brush 22 carried by the trailer arm 21, segment 60, conductor 61, contacts 57 of a relay 52, the winding of a relay 62 to a current bus 7, common to the opposite side of the current supply 8. The 105 relay 62 operates and completes a circuit from current bus 7, contacts 64 of this relay 62, conductor 65, the winding of a relay 66 (contact members of which are not shown), to the opposite bus conductor 9. 110

Passing now to the third and strongest impulse of positive current from the line conductor 1, current action through the transformer 4 exerts sufficient force on the operating coil 11 of the relay 10 to bring the tongue 12 first against the left-hand prong of the contact 16 and thereafter to flex or bend it sufficiently to also make contact with the left-hand prong of the contact 14. Since 10 the current bus 9 connects to the tongue 12, it follows that current therefrom will pass over the contacts 14 and 16 and conductors 15 and 17 respectively to energize the contactor rings 25 and 27 of the distributor 20. 15 The trailer arm 21 now over the segments 70 and 80 completes a circuit from the ring 25, brush 23, segment 70, conductor 71, the winding of a relay 72, to the current bus 7. The relay 72 thereby operated completes a circuit 20 through its contacts 74 from the bus 7, conductor 75, and the winding of a relay 76 to the current bus 9. A further result of the operation of the relay 72 is the separation of its contacts 77 to disable a relay 82 which 25 at this time would otherwise be operated by current from the ring 27 of the distributor traversing a brush 22, carried by but insulated from the arm 21, and segment 80 to a conductor 81 which now stands disconnected at the contacts 77 of the relay 72. It will be clear that the action resulting from the three impulses of current just described establishes the operation of relays 62, 72, 66 and 76, and through other responsive means 30 (not shown) such action effects the final selection and printing of the letter "F". Although not shown, it will be understood that suitable contact members may be carried by the relay coils 36, 46, 56, 66, 76 and 86, 35 such contact members to control selection of responsive means whereby all of the necessary operations of receiving and printing a message may be readily performed in a manner well-known and practised in the 40 printing telegraph art.

From the foregoing description it will be clear: first, that impulses of minimum strength do not result in action at the compound acting relay 10 or the distributor 20; 45 second, that currents of single step increment or mean strengths close only one contact at the relay 10 to energize the ring 27 associated with the segments 40, 60 and 80 at the distributor 20; and, third, that impulses 50 of two-step or two-fold incremented strength value close both contacts of the relay 10 to thereby energize each ring 25 and 27 of the distributor. It will be noted, however, that although both of the rings 25 and 27 of the 55 distributor may be energized at one and the same time, only one of an associated pair, formed respectively of relays 32, 42; 52, 62; and 72, 82; may be operated under a single impulse condition. This is due to the contacts 37, 57 and 77 of respective relays 32,

52 and 72 being adapted to disable corresponding relays 42, 62 and 82.

Referring to the distributor 20 it will be noted that segments 30, 50 and 70 are longer than segments 40, 60 and 80. This provides 70 a "lead" and "lag" for the respective energizing and deenergizing of the associated relays 32, 52 and 72. This feature insures that the respective contacts 37, 57 and 77 of these relays will not permit momentary or 75 stray currents to reach the windings of the relays 42, 62 and 82.

Referring to the alternate arrangement shown in Fig. 2 of the drawing, this modification differs from the first in that only 80 one contactor ring 25 and one set of associated segments 30, 50 and 70 are required on the distributor 20. In carrying out this change it will be noted that the current source is included between the tongue 12 of 85 the relay 10 and the ring 25 of the distributor, while the contacts 14 and 16 of the relay 10 are included respectively with the bus conductors of relays 32, 52 and 72 and 90 relays 42, 62 and 82. Accordingly, for an 95 impulse from the line 1 to connect the gold wire 12 with the contact 16 of the relay 10, circuit is thereby prepared from current source 8 through each relay 42, 62 and 82 to the respectively associated segments 30, 50 95 and 70 on the distributor. The synchronizing of the distributor 20 with three-unit code impulses as described for the first arrangement results in the trailer arm 21 being over one or another of these segments during the 100 action of an impulse. That is, for a first impulse of a three-unit code the trailer would be over segment 30; for a second impulse over the segment 50; and for a third impulse over the segment 70. It will, therefore, be clear that closure of the contacts 12 and 16 of the relay 10 would result in the operation of either relay 42, 62 or 82, depending on which of the three impulses of 105 a code was present from the line and the corresponding position of the trailer arm 21 with respect to the segment 30, 50 or 70. For a doubly incremented current impulse from the line 1, whereby member 12 of the relay 10 completes circuit with both contacts 14 and 16, thereby energizing the relay buses 15 and 17, the trailer arm 21 may only select either relay 32, 52 or 72, since the contacts 37, 57 and 77 of these relays 110 disable respectively the relays 42, 62 and 82. 115 In order to prevent stray or momentary flashes of current affecting the last-mentioned relays during a time circuit is completed to each one of the common conductors 15 and 17, it will be understood that 120 either by design or adjustment the relays 32, 52 and 72 may be adapted to respond more quickly than the relays 42, 62 and 82 and also to release in a relatively slow manner. Ordinarily, however, the circuit ar- 125 130

5 arrangement whereby the contacts of the relays 42, 62 and 82 are adapted to in turn operate other relays or electroresponsive devices (not shown) affords a sufficient so-called bug-trap guard to prevent interference in case all of the relays are of the same type or adjusted to the same operating characteristics.

10 Although a gold wire relay has for convenience been shown in connection with this invention, a suitable relay of other type may be readily substituted therefor.

15 For multiplex working a second receiving equipment similar to the present invention may be employed in connection with the three uppermost pairs of idle segments on the distributor 20. And also, in a suitable situation, a transmitting equipment may be substituted for the second transmitter and 20 employed to work a receiving equipment at the distant end of the line circuit.

What is claimed is:

1. In a telegraph system wherein the different characters of a message are represented by different combinations of alternating current impulses of various strengths, a line relay selectively responsive to impulses of different strength, in combination with a plurality of pairs of selecting relays, and 30 distributor means for successively connecting said line relay to said pairs of selecting relays.

2. In a telegraph system wherein the different characters of a message are represented by different combinations of alternating current impulses of various strengths, a line relay selectively responsive to impulses of different strengths, in combination with a plurality of selecting relays selectively responsive to the selective actuation 40 of said line relay, and distributor means for successively connecting said line relay to said selecting relays.

3. In a telegraph system, a selectively responsive line relay, a plurality of relays associated in pairs, a distributor for including said relays in pairs with said line relay, and contacts controlled by a relay in each of said pairs of relays to disable the other relay 50 of a pair.

4. In a telegraph system, a line relay selectively responsive to alternating currents of various strengths, a plurality of selecting relays associated in pairs, a distributor for selectively including said pairs of relays to 55 permit an individual relay to be selected by said line relay, and switching means controlled by said distributor to prevent stray momentary currents from affecting the non-selected relay of a pair.

In witness whereof, I hereunto subscribe my name this 10th day of July, A. D. 1917.

JOHN HUME BELL.
